FLOWER VASE

Filed Oct. 19, 1935

Inventor:
Sigmund Lee Wolffs
By Cox & Moore Attns.

UNITED STATES PATENT OFFICE

98,633

DESIGN FOR A FLOWER VASE

Sigmund Lee Wolffs, Chicago, Ill.

Application October 19, 1935, Serial No. 59,137

Term of patent 7 years

To all whom it may concern:

Be it known that I, Sigmund Lee Wolffs, a citizen of the United States, residing at Chicago, Cook County, Illinois, have invented a new, original, and ornamental Design for a Flower Vase, of which the following is a specification, reference being had to the accompanying drawing, forming a part thereof.

Figure 3 is a perspective view of the other side of the flower vase showing the new design.

I claim:

The ornamental design for a flower vase as shown.

SIGMUND LEE WOLFFS.
